PROJECTION APPARATUS FOR THE
CREATION OF ILLUSORY EFFECTS

Reynold B. Johnson, Binghamton, N. Y., assignor
to International Business Machines Corpora-
tion, New York, N. Y., a corporation of New
York

Application September 8, 1944, Serial No. 553,168

4 Claims. (Cl. 240—1)

1

The projection apparatus comprising the present invention is primarily adapted for use in the creation of illusory effects upon a projection screen simulating muzzle flash as it exists in the firing of a dual gun weapon of the type commonly employed in a turret installation of a combat plane. The invention is designed for use in connection with training apparatus of the type shown in my co-pending application Serial No. 553,167, filed September 8, 1944, for "Artillery training apparatus and method."

In the apparatus shown and described in the above mentioned co-pending application, a dummy weapon is employed for aiming at a moving target projected upon a motion picture projection screen. This weapon is in the form of a turret installation closely simulating an actual turret installation and having a pair of spaced dummy weapons carried on a tiltable gun mount. The gunner undergoing training is seated in a compartment between the two weapons and he is provided with most of the usual turret accoutrements common to such installations, including dual trigger devices and a gun sight. The training apparatus further includes a tracer projector which is located behind the dummy weapon installation for the purpose of placement projection of tracer effects on the screen which are correlated with the aiming and firing of the dummy weapons.

The present invention is designed to further enhance the optical effects produced upon the student gunner by creating the illusion of muzzle flash on the screen and in accomplishing this purpose a flash of light may be seen by the gunner when looking through the gun sight as each tracer shot is fired. The flash appears to leave the gun muzzle and converge upon the screen at the point of aim just as the tracer shot appears.

The projection unit comprising the present invention is mounted upon the turret gun cradle or gun mount at one side of the gun sight and is bodily movable with the cradle. The device is synchronized electrically with the turret controls so as to become operative only when tracer shots are discharged at the screen.

The provision of an apparatus of the character set forth being the principal object of the invention, a further object thereof is to provide a projection unit of this type which is relatively simple in its construction and which is comprised of a minimum number of moving parts and which, consequently, is unlikely to get out of order.

Another object of the invention is to provide such an apparatus which is electrically con-

2

trolled, thereby facilitating synchronization of the flash with the electrical firing of the dummy weapon.

A still further object of the invention is to provide a small portable projection apparatus capable of being attached to or removed from the dummy weapon at will and capable of being connected to the dummy weapon installation by detachable plug-in connections.

10 In carrying out the above mentioned object, the invention contemplates the provision of a continuously illuminated light source adapted to cast its light upon a movable mirror which is capable of oscillation about an axis. Light issuing from the source and striking the mirror is deflected from the surface of the moving mirror onto a reflector and from thence onto the screen, the tendency being to project a moving beam of light onto the screen and cause the same to move across the screen from left to right and from right to left alternately. Because of the fact that such a beam of light in passing across the screen in that region thereof which exists directly at the point of aim would ordinarily tend 15 to obscure the tracer effects produced by the training projector, means are provided for blanking out the spot as it approaches the point of aim. Toward this end, shutter means are provided for the light source which become operable periodically to block light issuing from the source at a predetermined time. The provision of an apparatus possessing this feature is a still further important object of the present invention.

20 25 30 35 Further objects and advantages of the invention not at this time enumerated will become more readily apparent as the nature of the invention is better understood.

In the accompanying two sheets of drawings forming part of this specification, one embodiment of the invention is shown. In these drawings:

Fig. 1 is a side elevational view of the projection unit with one side wall of its casing im-
45 proved and certain other parts being broken away to more clearly reveal the nature of the invention.

Fig. 2 is a sectional view taken substantially along the line 2—2 of Fig. 1.

50 Fig. 3 is a sectional view taken substantially along the line 3—3 of Fig. 1.

Fig. 4 is a sectional view taken substantially along the line 4—4 of Fig. 1.

55 Fig. 5 is a diagrammatic view showing the electrical connections for the projection apparatus.

Referring now to the drawings in detail, the apparatus involves in its general organization a rectilinear box-like casing 8 adapted to be detachably secured in a suitable position to the tiltable gun mount or cradle of a dummy weapon substantially as shown in my co-pending application above referred to. The casing 8 includes a base plate 10 on which there is mounted a bracket 12 which serves to support a mounting 14 for a lamp 1. A lens 16 mounted in a bracket 18 serves to concentrate light issuing from the lamp 1 into a beam and to project the latter against the surface of a movable mirror 20 positioned behind the lamp. From the movable mirror 20 the light beam is projected against the surface of a stationary mirror 22 mounted on a bracket 24 supported on the side pieces 26 of an inverted U-shaped frame 28 supported on the base plate 10. From the stationary mirror 22 the light beam is projected onto a screen (not shown) associated with the trace trainer apparatus.

The movable mirror 20 is mounted on a fixture 30 which in turn is mounted on a horizontal rock shaft 32 suspended in brackets 34 and 36. The movable mirror 20 is inclined with respect to the shaft 32 in such a manner that light issuing from the lens 16 will be reflected generally upwardly against the stationary mirror 22 which is of elongated design and extends completely across the unit between the side members 26.

A pair of solenoids 38 and 40 are mounted on a support 42 carried by the base plate 10 and are provided with cores 44 that are pivoted medially of respective links 46, which in turn are pivoted to fixed lugs 48 mounted on the upper ends of the solenoids. The free end of each link 46 is pivotally attached to a connecting rod or link 50 and the lower ends of the links 50 are secured to the opposite ends of a cross head 52 centered on the shaft 32. The solenoids 38 and 40 exist in respective electrical circuits by means of which alternate energization thereof is made possible to cause oscillation of the cross head 52 and consequent oscillation of the shaft 32 and movable mirror 20 about a horizontal axis. The electrical circuits for the solenoids 38 and 40 will be pointed out subsequently during the description of the electrical diagram for the unit.

The bracket 36 is comparatively wide and in addition to performing a support for the rock shaft 32 also serves to rotatably support one end of a second rock shaft 54, the other end of which shaft is rotatably supported in a bracket 56 positioned near and to one side of the lamp assembly. An arm 58 secured to the rock shaft 32 projects outwardly therefrom and is provided with a slot 60 adjacent its free end. A similar arm 62 carried by the shaft 54 is provided with a pin 64 adjacent its outer end which passes through the slot 60 for the purpose of mechanically coupling the two shafts 32 and 54 together. It will be seen that by the arrangement of parts just described the oscillatory motion of the shaft 32 will be transmitted to the shaft 54. The forward end of the shaft 54 immediately behind the bracket 36 has mounted thereon a pair of shutter operating arms 66 which project outwardly from the shaft 54 and the ends of which are turned laterally as at 68. A bracket 70 secured to the base plate 10 serves to support adjacent its upper end a rock shaft 72 from which there projects laterally a shutter member 74 including a shutter arm 76 and a shutter proper 78. The two laterally extending portions 68 of the operating arms 66 straddle the shutter arm

76 in such a manner that upon oscillation of the shaft 54 these lateral portions of the operating arms 66 are adapted to alternately engage the shutter arm 76 to bring the shutter 78 directly in front of the light source or lamp 1 and block the rays of light issuing therefrom. The laterally extending portions 68 of the shutter operating arms 66 are spaced apart a distance somewhat greater than the width of the shutter arm 76 so that a considerable degree of lost motion exists between the movements of the shutter and of the shutter operating arms. By such an arrangement, the shutter is maintained out of registry with the lamp 1 during the movement of the movable mirror 20 at the commencement of its stroke in either direction. This permits a flash of light upon the screen to sweep in one direction or the other inwardly of the screen until the shutter 78 becomes effective to block light rays issuing from the lamp 1. After this occurs no further light is permitted to reach the screen until after the mirror has completed its stroke. The movements of the shutter 78 and of the mirror 20 are so correlated that the net result consists of a flash of light which appears on the screen each time a tracer shot is fired. This flash alternately sweeps inwardly from the sides of the screen and converges toward the point of aim of the dummy guns associated with the trace trainer installation. These flashes of light are observed by the operator seated in the turret compartment of the assembly on opposite sides of the two gun units.

A cover plate or casing 80 including side walls 82, a top wall 84 and a rear wall 86 is provided for the mechanism just described. The front end of the casing 8 is open in the upper regions thereof and a shield 88 is associated with the casing 8 to restrict issuance of light from the lamp 1 and confine the light to the mirror 20. The passage of light from the lamp 1 and its deflection by the mirrors 20 and 22 onto the screen is graphically illustrated by means of small arrows in Fig. 1.

Referring now to Fig. 5 wherein the circuit diagram for the projection apparatus is disclosed, the lamp 1 receives energization from the secondary coil s of a transformer T having a primary winding p adapted to be energized from a source of current S which may, if desired, be the usual 110-volt, 60-cycle alternating household current.

The solenoid 38 is provided with a winding S1 and the solenoid 40 is provided with a winding S2, the two windings being connected together in parallel and having a common lead a in which there is interposed a source of current which may, if desired, be a battery B. The windings S1 and S2 are connected by wires b and c to respective brushes b' and b'' associated with a rotor r adapted to be continuously driven from a motor M. The rotor r carries a movable contact C operable upon rotation of the rotor r to alternately engage the brushes b' and b'' and thus alternately energize the solenoids 38 and 40. A switch tc which may be in the form of a trigger mechanism serves to open the circuit of the motor and the common lead a of the solenoid windings S1 and S2.

The invention is not to be limited to the exact arrangement of parts shown in the accompanying drawings or described in this specification as various changes in the details of construction may be resorted to without departing from the spirit of the invention. Only insofar as the in-

vention has been particularly pointed out in the accompanying claims is the same to be limited.

What is claimed is:

1. In a projection apparatus for producing moving light effects which are representative of tracer bullet flash upon a projection screen, a movable mirror mounted for oscillation about an axis, a light source positioned in front of said mirror, a movable shutter positioned between said light source and mirror and movable from a position out of the path of light issuing from said source and passing to the screen to a position in the path of movement of such light, means operatively connecting said mirror and shutter to synchronize the movements thereof whereby said shutter assumes an inoperative position when said mirror is in the vicinity of either of its extreme positions and assumes an operative position when said mirror is in the vicinity of its medial position, and means for moving said mirror.

2. In a projection apparatus for producing moving light effects upon a projection screen, a horizontal rock shaft, a mirror mounted upon said rock shaft for oscillation therewith and inclined with respect to the axis of said shaft, an electromagnet operable upon energization thereof to move said rock shaft in one direction to an extreme position, a second electromagnet operable upon energization thereof to move said rock shaft in the opposite direction to an extreme position, a second rock shaft mounted for rotation about a horizontal axis, a light source positioned in front of said mirror, a shutter secured to said second rock shaft and movable with the shaft from an inoperative position wherein it is out of the path of movement of light issuing from said source and proceeding to the mirror to an operative position wherein it intercepts such light, means for alternately energizing said electromagnets to impart oscillating movement to said first mentioned rock shaft, and means including a lost motion connection operatively connecting said rock shafts to transmit motion from the former to the latter.

3. In a projection apparatus for producing moving light effects upon a projection screen, a horizontal rock shaft, a mirror mounted upon said rock shaft for oscillation therewith and inclined with respect to the axis of said shaft, an electromagnet operable upon energization thereof to move said rock shaft in one direction to an extreme position, a second electromagnet operable upon energization thereof to move said rock shaft in the opposite direction to an extreme position,

sition, a second rock shaft mounted for rotation about a horizontal axis, a light source positioned in front of said mirror, a shutter secured to said second rock shaft and movable with the shaft from an inoperative position wherein it is out of the path of movement of light issuing from said source and proceeding to the mirror to an operative position wherein it intercepts such light, means for alternately energizing said electromagnets to impart oscillating movement to said first mentioned rock shaft, a third rock shaft mounted for oscillation about a horizontal axis, means operatively connecting said first mentioned rock shaft to said third mentioned rock shaft to transmit motion from the former to the latter, and means including a lost motion connection operatively connecting said third mentioned rock shaft to said second mentioned rock shaft to transmit motion from the former to the latter.

4. In a projection apparatus for producing moving light effects upon a projection screen, a rock shaft mounted for rotation about a horizontal axis, a mirror mounted on said rock shaft for oscillation therewith and inclined with respect to the axis thereof, an electromagnet operable upon energization thereof to move said rock shaft in one direction to an extreme position, a second rock shaft mounted for rotation about a horizontal axis, a light source positioned in front of said mirror, a shutter carried by said second rock shaft and movable from an inoperative position where it is out of the path of light issuing from said source and proceeding so the movable mirror to an operative position where it intercepts such light, a third rock shaft mounted for oscillation about a horizontal axis, an arm secured to said first mentioned rock shaft and projecting laterally therefrom, an arm secured to said third mentioned rock shaft and projecting laterally therefrom, there being a slot in one of said arms, a pin carried by the other arm and projecting through said slot whereby motion of said first mentioned rock shaft is imparted to said third mentioned rock shaft, a pair of diverging arms secured to said third mentioned rock shaft and having laterally turned ends which straddle said shutter, the distance between said laterally turned ends being greater than the width of said shutter in the region of contact therewith, and means for alternately energizing said electromagnets.

REYNOLD B. JOHNSON.
